ORIFICE CONSTRUCTION

Milner Noble, Newark, N. J., assignor, by mesne assignments, to Carrier Corporation, Newark, N. J., a corporation of Delaware

Application June 30, 1936, Serial No. 88,109

2 Claims. (Cl. 210—164)

This invention relates to the construction of orifices for the passage of fluid, and more particularly to the construction of orifices for supplying fluid to the tubes of heat exchangers.

In the art of heat exchange, it is common practice to supply a heating or cooling medium to a header serving a plurality of tubes about which there is circulated a fluid to be heated or cooled. The heating or cooling medium is supplied to the tubes from the header through orifices. After the heating or cooling medium has circulated through the tubes and has been in heat exchange with the fluid to be heated or cooled, it is returned to a boiler, refrigeration machine, of the like, to be prepared for a repetition of its heat exchange function.

In the past, considerable difficulty has been occasioned by clogging and stoppage of the orifices, by scale and other foreign matter carried to the orifices by the heating or cooling medium.

The general object of the invention is to provide an improved orifice construction in which clogging and stoppage of the orifice by scale and other foreign matter is greatly reduced.

It is another object of the invention to provide an orifice construction which will assure uninterrupted supply of fluid to a tube served by the orifice, notwithstanding the carrying to the orifice of particles of material which would completely clog orifices of conventional design.

It is another object of the invention to provide an orifice construction which will assist in the breaking up of scale and particles of foreign matter carried thereto, whereby the small particles may readily pass through the orifice and into the tube, without interrupting or interfering with the supply of heat exchange medium to the tube.

It is another object of the invention to provide an orifice construction which is relatively simple, inexpensive to manufacture, self-cleaning, and highly effective in passing fluid in uninterrupted and substantially uniform flow.

A feature of the invention resides in the provision of a member having one or more elements extending from an orifice opening in a direction counter to that of fluid flow through the orifice. These elements serve to catch and hold particles of scale and other foreign matter which would clog conventional orifices, and prevent these particles from restricting the flow of fluid through the orifice opening.

Another feature of the invention resides in the provision of a member having a plurality of crown points surrounding an orifice opening, the

points being relatively sharp, in order to break up particles of scale or other foreign matter impinging thereagainst or caught thereon.

Other objects, features and advantages of the invention will be more apparent from the following description, to be read in connection with the accompanying drawing, in which:

Fig. 1 represents diagrammatically a heat exchange system including a tubular heat exchanger; and

Fig. 2 is a sectional elevation of a portion of the tubular heat exchanger of Fig. 1, illustrating an improved orifice construction embodying the invention.

Referring now to the drawing, similar designations referring to similar parts, 10 represents a boiler, refrigerating machine or the like, in which a conditioning or heat exchange medium is heated or cooled, and 11 represents generally a heat exchanger in which the heated or cooled medium is used for heating or cooling a fluid, such as air or water, passed in contact with the tubes 12. Heated or cooled medium from 10 is passed through supply line 13 to inlet header 14, whence it is passed through orifices generally designated 15 to the tubes 12. Conditioning medium which has passed through the tubes 12 is collected in outlet header 16 and returned to 10 through return line 17.

Referring more particularly to Fig. 2, the inlet end of each tube 12 is capped by a crown-shaped member 18, having at its lower extremity an annular flanged portion 19 which abuts the end of the tube, and having a plurality of crown points 18a, extending toward the inlet header. The crown points 18a are preferably, but not necessarily, of unequal height, and the longer points may extend into the inlet header 14. An annular recess 20, formed in the tube-receiving portion 21 of the header 14, surrounds the crown points 18a. Preferably, the inside diameter of the annular flanged portion 19 is smaller than the inside diameter of the tube 12, so that the member 18 provides a somewhat restricted orifice for the tube. Such restriction is desirable to develop a considerable pressure differential between the inlet and outlet headers, in order to prevent air-binding of the heat exchanger. When tubes having a relatively small inside diameter are used, however, there is a relatively great pressure drop through the tubes, and there is no necessity for providing a restricted inlet opening. In such case, the separate member 18 may be dispensed with, and the crown points may be formed by cutting out portions of the end of the tube.

55

When conditioning medium supplied to the tube contains particles of scale or other foreign matter, which would clog orifices of conventional design, these particles are caught upon the crown points 18a. Since the points are relatively sharp, such particles are frequently broken up into pieces sufficiently small to pass through the orifice without interfering with the flow of fluid; thus there is a self-cleaning action. Even when such breaking up of the particles is not effected, however, applicant's construction provides for the uninterrupted supply of fluid to the tube. If scale or foreign matter is caught upon the crown points in such manner as to clog the opening at the upper end of member 18, fluid continues to flow to the orifice and tube 12 at undiminished rate through the V-shaped weirs between the crown points; and even though some of the weir openings should become clogged, flow through the others would continue to supply fluid to the tube 12. In practice, it has been found that the supply of fluid to applicant's tubes is practically never interrupted by clogging, because of the great number of openings or paths provided for feeding fluid to the tubes, and because of the self-cleaning action of applicant's orifice construction.

While applicant's member 18 is illustrated and described as being provided with openings which comprise V-shaped weirs, openings of any other

shape or type may be utilized without departing from the scope of the invention. Moreover, while the crown points 18a are shown as being parallel to the direction of flow through the orifice, the crown points may be inclined convergingly or divergingly, if desired.

Since many modifications may be made in the invention without departing from its scope, applicant intends that the above description and accompanying drawing be considered as illustrative only, applicant limiting himself only as indicated in the appended claims.

I claim:

1. An anti-clogging orifice guard comprising a hollow crown-shaped member having a plurality of peripherally arranged crown points of unequal length extending substantially parallel to the direction of fluid flow through the orifice to be protected and in a direction counter to said direction of fluid flow.

2. An anti-clogging orifice guard comprising a hollow base portion and a plurality of peripherally arranged crown points, said crown points extending substantially parallel to each other away from the orifice to be protected, said crown points diminishingly tapering away from said base portion to provide a plurality of relatively sharp points at the extremities of said crown points.

MILNER NOBLE.
